UNITED STATES PATENT OFFICE

2,424,126

ELECTRIC CIRCUIT BREAKER

Sidney R. Smith, Jr., Pittsfield, Mass., assignor
to General Electric Company, a corporation of
New York

Application May 11, 1940, Serial No. 334,629

39 Claims. (Cl. 200—116)

1

My invention relates to electric circuit breakers and more particularly to such circuit breakers which are adapted for use in place of the conventional fuse cutout devices.

Fuse cutout devices have been used to a large extent in the protection of high-tension electric circuits. Devices of this type in general comprise replaceable fusible means mounted within a suitable holder and they are usually located in close proximity to the high-tension conductors as a consequence of which they are relatively inaccessible for inspection and maintenance. Difficulties have been encountered in providing cutouts having an electric fuse convenient for installation and inspection and, at the same time, capable of being removable and replaceable. In any event, an abnormal electrical condition occurring on a circuit protected by a fuse cutout will destroy the fuse and, hence, require replacement thereof. Although recent experimentation and research have reduced the cost of the replaceable elements, nevertheless such cost is still appreciable and it would be desirable to provide a fuseless cutout which will automatically interrupt the circuit under abnormal electrical conditions and yet wherein it is unnecessary to replace any elements after the protective operation of such cutouts as is necessary with the fuse cutouts of the prior art.

It is an object of my invention, therefore, to provide a new and improved circuit breaker adapted to replace the fuse cutouts of the prior art.

It is another object of my invention to provide a new and improved fuseless cutout which is simple and compact and which may be used in connection with the prior-art holders for fuse cutouts.

It is a further object of my invention to provide a fuseless cutout for protecting electrical apparatus which is simple, compact, and economical in construction, and which, at the same time, gives an immediate and reliable indication of the actuation and condition of the protecting device.

Still another object of my invention is to provide a fuseless cutout which is rugged, compact, and strong in construction, dependable in operation, and well adapted to meet the varying conditions of actual practical use.

Further objects and advantages of my invention will become apparent as the following description proceeds and the features of novelty which characterize my invention will be pointed out with particularity in the claims annexed to and forming a part of this specification.

For a better understanding of my invention, reference may be had to the accompanying drawings in which Fig. 1 is a view partly in section of my fuseless cutout in the normal operative position; Fig. 2 is a similar view of the device after the circuit has been interrupted; Fig. 3 is a cross-sectional view taken on line 3—3 of Fig. 1; Fig. 4 is a front view of the circuit breaker mounted on the door of the fuseless cutout holder; Fig. 5 is a cross-sectional view of the circuit breaker in the operative position of Fig. 1; Fig. 6 is a view partly in section illustrating the device of my invention at one instant during the circuit-interrupting interval, and Fig. 7 represents one step in the resetting of the fuseless cutout of my invention.

Referring now to the drawings, I have illustrated my invention in connection with a housing 10 of porcelain or similar insulating material of the size and shape used in connection with the fuse cutouts of the prior art, such as is disclosed, for example, in United States Letters Patent 2,081,826, granted May 25, 1937, upon an application of George F. Lincks, and assigned to the same assignee as the present application. Housing 10 is preferably provided with an integrally formed electric creepage and gas barrier 11 disposed between stationary line terminal contacts 12 and 13 carried by the housing. To the rear 30 of the housing or casing 10 is secured a mounting bar 14 for the attachment of the casing to an electric line pole and cross-arm structure or the like. A pair of hinge brackets 15, only one of which can be seen in the drawings, are secured to the inner face of the rear wall of the casing 35 adjacent the bottom thereof for engagement with a rod-shaped pivot member 16 associated with the circuit-breaker assembly to be described hereinafter. Hinge brackets 15 comprise spring-biased jaws 15a and 15b between which pivot member 16 may readily be inserted but which provides good electrical contact at the hinge joint.

Contacts 12 and 13 are adapted to have line 45 conductors or leads fastened thereto by means of clamping screws 12' and 13', respectively, and upper contact 12 has a contact finger 17 backed up by means of a spring strip 18 which serves to press the finger 17 downwardly and has also 50 a pair of spaced resilient contact fingers 19, only one of which can be seen in the drawings, backed up by means of a spring strip 20. These contact fingers 19 are arranged to receive the terminal cap 21 of my improved circuit breaker which is 55 similar to the terminal cap of the fuse holders

of the prior art. Contact 13 is electrically connected with pivot member 16 by virtue of jaws 15a and 15b of hinge bracket 15.

A door or cover 22 preferably constructed of insulating material is provided for housing 10 and suitably supports at 23 the door-mounted electric circuit breaker 24 to be described hereinafter. On the outer face of door or cover 22, there is formed an eyelet handle 25 which may be either grasped manually or engaged by a suitable switch stick 26, shown in Fig. 7, for interrupting the electric circuit as by swinging the door and associated circuit breaker outwardly upon pivot member 16 held by the jaws 15a and 15b of hinge brackets 15 or bodily removing door 22 from housing 10. Door 22 is held in position in housing 10 by spring pressed contact fingers 17 and 19 which engage terminal cap 21 of the door-mounted circuit breaker 24 at the upper end thereof and jaws 15a and 15b of hinge brackets 15 which engage pivot member 16 of the door-mounted circuit breaker 24 at the bottom thereof.

In order that my fuseless cutout be compact and of substantially the same size as the fuse cutouts of the prior art, I provide a door-mounted circuit breaker 24 which comprises two electric circuits connected in parallel with one another. The first of these circuits comprises the main current-conducting path through which the power flow takes place under normal conditions. This path extends from terminal cap 21 which is threadedly supported by a conducting member 27 through a latching means 28, a pair of flexible conductors 29, a pair of main switching means 30 comprising relatively movable contacts 30a and 30b, a pair of flexible connectors 31, and a conducting slidable member 32 integrally connected with supporting pivot pin 16. Contacts 30a are stationary and are mounted to support 23 attached to door 22. Contacts 30b, on the other hand, are movable and are suitably fastened as by welding to an annular-shaped conductor 33, which is provided with an integrally connected hook 34 for engaging with slidable member 32, as will be pointed out hereinafter, and an integrally mounted keeper 35 for engagement with a roller 36 supported by latching means 28.

Relative movement between contacts 30a and 30b is obtained by virtue of an energy-storage means comprising tension spring 37 connected between hook 34 and slidable member 32 so as to bias movable contacts 30b away from stationary contacts 30a to interrupt the main current-carrying path through circuit breaker 24. The movement of contacts 30b is guided by means of insulating expulsion tube 38 described in greater detail hereinafter along which annular-shaped conductor 33 which encircles tube 38 is adapted to slide. Tube 38 is supported along with stationary contacts 30a by member 23 fixedly attached to door 22 and, in turn, supports conducting member 27 to which terminal cap 21 is attached.

When roller 36 of latching means 28 engages keeper 35, relatively movable contacts 30a and 30b of switching or isolating means 30 are held in conducting engagement. Any suitable means may be provided for releasing latching means 28 so that the energy-storage means comprising tension spring 37 causes separation of contacts 30a and 30b. Such means may comprise a magnetic trip or, as illustrated in the drawings, a thermal-responsive trip may be provided. Accordingly, I

have shown latching means 28 constructed as a bimetallic element through which substantially all the current flows when contacts 30a and 30b are in engagement. An abnormal current condition on the power lines associated with my fuseless cutout will cause heating of bimetallic latching means 28 and consequent deflection thereof as shown in Figs. 2 and 6 so that roller 36 releases keeper 35 whereupon tension spring 37 causes separation of contacts 30a and 30b.

Manual means for tripping latching means 28 are provided in the form of a pair of hook-shaped fingers 39, suitably supported from the rear wall of housing 10, which engage with extensions 40 of a pivot pin upon which roller 36 is mounted. If door 22 of housing 10 is opened, fingers 39 engaging extensions 40 will cause deflection of latching means 28 so that roller 36 releases keeper 35, whereupon the energy stored in tension spring 37 is again released to cause separation of contacts 30a and 30b.

It will be understood by those skilled in the art that contacts 30a and 30b, as shown, are not capable of satisfactorily interrupting large values of current at high voltage and, accordingly, I provide an additional circuit including relatively movable arcing contacts 41 and 42, Figs. 5 and 6, connected in parallel with the circuit including bimetallic latching means 28 and contacts 30a and 30b. These arcing contacts 41 and 42 are arranged to interrupt the circuit through circuit breaker 24 within expulsion tube 38 which is preferably constructed of an insulating material of the type from which arc-extinguishing gas is evolved under the influence of the heat of an electric arc. It will, of course, be understood by those skilled in the art that expulsion tube 38 may be constructed of ordinary insulating material and lined with a material of the gas-evolving type. Arcing contacts 41 and 42 are preferably constructed of a suitable arc-resistant material, such as tungsten, for example.

Under normal conditions, it is desirable that substantially of the current flowing through circuit breaker 24 be carried by main current-carrying contacts 30a and 30b and bimetallic latching means 28 while very little current is carried by arcing contacts 41 and 42. In order to provide for this current division between the parallel conducting paths of circuit breaker 24, arcing contacts 41 and 42 may be connected in series with an impedance to current flow, such as a small gap, or, as illustrated in Fig. 5, with a resistance 43. This resistance 43 may comprise a block of carbon although, in order that the voltage across resistance 43 may be held to a low value regardless of the current passing therethrough, it is preferable that resistance 43 be constructed of a material having an inverse voltage resistance characteristic. One such resistance material is commercially available under the trade name "Thyrite" and is described and claimed in United States Letters Patent No. 1,822,742, granted September 8, 1931, upon an application of Karl B. McEachron. It will, of course, be understood by those skilled in the art that a resistance having a positive voltage resistance characteristic may also be employed even though not quite so satisfactory. In some cases, it may also be desirable to omit resistance 43 since an arcing rod 44 connected in series with arcing contact 42 may be provided of a material, such, for example, as stainless steel having a somewhat higher resistance than conducting materials, such as copper.

Arcing rod 44 extends for the major length of expulsion tube 38 and is suitably connected to annular conducting ring 33 by a U-shaped conducting member 45, best shown in Fig. 4. Arcing contact 41, on the other hand, is electrically connected with terminal cap 21 by means of flexible conductor 46, see Figs. 5 and 6, which, in turn, is in conducting relationship with resistance 43. It will be understood that, if resistance 43 is omitted, flexible conductor 46 will be directly connected to terminal cap 21. As illustrated in Figs. 5 and 6, resistance 43 is preferably surrounded by suitable insulation 47 so that only the ends thereof are in conducting relation with terminal cap 21 and flexible connection 46. A suitable compression spring 48 tends to bias contact 41 toward contact 42 until the full extent of flexible conductor 46 is reached. Arcing contacts 41 and 42 are so constructed and arranged with respect to main current-carrying contacts 30a and 30b that the latter are disengaged first so that all the current is transferred to the parallel circuit including arcing contacts 41 and 42. Thereafter, the circuit is interrupted in expulsion tube 38 and the arc drawn rapidly extinguished under the expulsion principle by virtue of the arc-quenching gases evolved from the walls of expulsion tube 38 or, if provided with a liner, from the liner.

Slidable member 32, to which is integrally mounted pivot pin 16, is constructed so as to engage a pair of grooves 49, Fig. 3, formed in a T-shaped extension 22a on the inner wall of door 22. This extension is also provided with a slot 50, see Fig. 3, through which hook 34 is adapted to slide. Slidable member 32 is provided with an extension 51 which encircles expulsion tube 38 and is slidable therealong and, furthermore, supports pivot pin 16. This extension 51 is provided with slots 52 on either side thereof for guiding U-shaped conducting member 45 during circuit-interrupting operation and, at the same time, maintaining arcing rod 44 substantially in the center of expulsion tube 38. The T-shaped extension 22a on the inner wall of door 22 is provided with an abutment 53, see Fig. 5, for holding slidable member 32 in the lower position so as to stress spring means 37 when main current-carrying contacts 30a and 30b are held in engagement by latching means 28. Hook 34 is constructed to engage slidable member 32 as shown in Fig. 2 to limit the downward movement of conducting ring 33 and associated movable contacts 30b.

It will be understood that U-shaped conducting member 45 provides an indicating means to show the condition of the circuit breaker 24 of my fuseless cutout. When the circuit breaker is closed, as in Fig. 1, the U-shaped conducting member 45 is completely within casing or housing 10, whereas, if the circuit is open, as in Fig. 2, member 45 extends out of the bottom of housing 10 to indicate clearly to the lineman that the circuit is open.

The operation of my fuseless cutout will be briefly described with reference first to Figs. 1, 4, and 5, where the circuit breaker 24 is shown in the closed-circuit position. Due to the higher resistance of the conducting path including arcing contacts 41 and 42 by virtue of the resistance of arcing rod 44 or resistance 43 if provided, substantially all the current passing through circuit breaker 24 is carried by bimetallic latching means 28 and main current-carrying contacts 30a and 30b. In the event of an abnormal current con-

dition, the resultant heating of bimetallic latching means 28 will cause a deflection thereof, as shown in Figs. 2 and 6, so that roller 36 releases keeper 35 and allows spring means 37 to cause separation of contacts 30a and 30b and eventually also of arcing contacts 41 and 42.

Due to the fact that spring 48 causes arcing contact 41 to follow arcing contact 42 during the initial opening movement of circuit breaker 24, as shown in Fig. 6, contacts 30a and 30b are disengaged while arcing contacts 41 and 42 are still in engagement. The current which normally flowed through bimetallic latching means 28 and current-carrying contacts 30a and 30b is, therefore, transferred to the parallel path including arcing contacts 41 and 42 and resistance 43. Further movement of arcing rod 44 and arcing contact 42 will cause an arc to be drawn between contacts 41 and 42 which will be rapidly extinguished by the explosive action of the arc-quenching gases evolved from the walls of expulsion tube 38 under the influence of the arc drawn.

Arcing contacts 41 and 42 and main current-carrying contacts 30a and 30b will be separated by a distance determined by the point at which hook 34 sliding in slot 50 engages with the upper edge of slidable member 32. Arcing rod 44 and associated U-shaped conductor 45 will extend from the lower end of housing 10 in the open-circuit position of circuit breaker 24 so as to give a clear indication to the lineman of the condition of the fuseless cutout. This may clearly be observed by comparing Figs. 1 and 2. In Fig. 1, arcing rod 44 and conductor 45 are completely contained within housing 10 whereas, in Fig. 2, they extend for a considerable distance outside of housing 10.

In order to reset the circuit breaker after the circuit has been interrupted, as shown in Fig. 2, the operator may employ a switch stick 26, as shown in Fig. 7, by means of which door 22 is pulled downwardly, to cause disengagement of terminal cap 21 and contact fingers 19, to the position shown in Fig. 7. This is possible by virtue of the fact that slidable member 32 has been caused to disengage from abutment 53 by the wedge-shaped portion of hook 34, best shown in Fig. 2. When the door 22 is pulled downwardly to the position shown in Fig. 7, current-carrying contacts 30a and 30b are engaged and the roller 36 of latching means 28 may reengage with keeper 35. Thereafter, door 22 is moved upwardly to cause slidable member 32 to move downwardly, stressing spring means 37 until slidable member 32 reengages with abutment 53, whereupon door 22 is closed so that terminal cap 21 is again engaged by contact fingers 17 and 19 and the circuit is again completed through circuit breaker 24.

It will be observed that, with my circuit breaker, bimetallic latching means 28 carries the high current only during the heating period after which it trips and no longer carries any current. This is particularly advantageous since, if there is an appreciable arcing time and the bimetallic latch carried the current during all this time, it might very likely be damaged or destroyed.

As will also be evident from the foregoing description, the present invention provides pronounced advantages over the fuse cutouts of the prior art in that it is unnecessary to replace any parts before the circuit may again be completed after a circuit interruption, it being merely necessary for the lineman to reclose the circuit breaker

in the manner described above. Furthermore, an indication of the condition of the fuseless cut-out is at all times evident to the linemen.

While I have shown and described a particular embodiment of my invention for a fuseless cut-out, I do not desire my invention to be limited to the construction shown and described for it will, of course, be obvious to those skilled in the art that changes and modifications may be made without departing from my invention and I, therefore, aim in the appended claims to cover all such changes and modifications as fall within the true spirit and scope of my invention.

What I claim as new and desire to secure by Letters Patent of the United States is:

1. In an electric circuit interrupter, a pair of relatively movable current-carrying contacts, means for maintaining said contacts in current-conducting relationship, means for separating said contacts in response to abnormal current conditions, a relatively high-resistance path connected in parallel with said current-carrying contacts and said abnormal current responsive means including a pair of relatively movable arcing contacts, an expulsion tube within which said arcing contacts are arranged to separate, said current-carrying contacts and said arcing contacts being so constructed and arranged that the former separate prior to the latter so that the current carried by said current-carrying contacts is diverted to said relatively high-resistance path to be interrupted subsequently by said arcing contacts.

2. In an electric circuit interrupter, a pair of relatively movable current-carrying contacts, means tending to bias at least one of said contacts to the open-circuit position, conducting means connected in series with said contacts for holding said contacts in current-conducting relationship, said last-mentioned means being responsive to abnormal current conditions for allowing separation of said contacts, a relatively high-resistance path connected in parallel with said serially connected current-carrying contacts and said last-mentioned means including a pair of relatively movable arcing contacts, said current-carrying contacts being arranged to separate prior to the separation of said arcing contacts so that the current carried thereby is diverted to said relatively high-resistance path to be interrupted by said arcing contacts.

3. In an electric circuit interrupter, an expulsion tube, a pair of relatively movable arcing contacts mounted therein, a conducting path connected in parallel with said arcing contacts for carrying substantially all the current flowing through said circuit interrupter under normal current conditions comprising a pair of relatively movable current-carrying contacts and latching means for holding said current-carrying contacts in engagement, said latching means being releasable in response to abnormal current conditions, means connected in series with said arcing contacts for causing substantially all the current carried by said circuit breaker to flow through said parallel conducting path when said current-carrying contacts are in engagement, means for causing separation of said current-carrying contacts upon release of said latching means to divert said current from said conducting path to said arcing contacts, and means for causing subsequent separation of said arcing contacts to interrupt the circuit in said expulsion tube.

4. In an electric circuit interrupter, a pair of relatively movable current-carrying contacts, spring means tending to cause separation of said

contacts, a bimetallic latch connected in series therewith for holding said contacts in conducting engagement and responsive to abnormal current conditions for releasing said spring to cause separation of said contacts, a relatively high-resistance path connected in parallel with said current-carrying contacts and said bimetallic latch including a pair of relatively movable arcing contacts, an expulsion tube within which said arcing contacts are arranged to separate, said current-carrying contacts being arranged to separate prior to the separation of said arcing contacts so that the current carried thereby is diverted to said relatively high-resistance path to be interrupted in said expulsion tube by said arcing contacts.

5. In a circuit interrupter, the combination of a housing comprising a casing and a door for closing an open side of said casing, an electric circuit breaker mounted on said door and comprising a pair of relatively movable current-carrying contacts, means for maintaining said contacts in current-conducting relationship, means for separating said contacts in response to abnormal current conditions, a relatively high-resistance path connected in parallel with said current-carrying contacts and said abnormal current responsive means including a pair of relatively movable arcing contacts, said current-carrying contacts being arranged to separate prior to the separation of said arcing contacts so that the current carried thereby is diverted to said relatively high-resistance path to be interrupted by said arcing contacts and means dependent upon the opening of said door for effecting the closure of said current carrying contacts.

6. In a load-disconnecting device, the combination of a casing and a door for closing an open side of said casing, a circuit interrupter mounted on said door comprising a pair of relatively movable contacts, latching means for holding said contacts in current-carrying relationship, and means for causing release of said latching means upon opening the door of said casing.

7. In an electric circuit interrupter, the combination of a casing and a door for closing an open side of said casing, a circuit breaker mounted on said door comprising a pair of relatively movable current-carrying contacts, means for maintaining said contacts in current-conducting relationship, means for separating said contacts in response to abnormal current conditions, a current-conducting path in parallel with said current-carrying contacts including a pair of relatively movable arcing contacts, an expulsion tube within which said arcing contacts are arranged to separate, and means for tripping said first-mentioned means upon opening the door of said casing for interrupting the circuit through said circuit breaker.

8. In an electric circuit interrupter, the combination of a casing and a door for closing an open side of said casing, a circuit breaker mounted on said door comprising a pair of relatively movable current-carrying contacts, means for maintaining said contacts in current-conducting relationship, means for separating said contacts in response to abnormal current conditions, a relatively high resistance path connected in parallel with said current-carrying contacts including a pair of relatively movable arcing contacts, an expulsion tube within which said arcing contacts are arranged to separate, said current-carrying contacts and said arcing contacts being so constructed and arranged that the former separate

prior to the latter so that the current carried by said current-carrying contacts is diverted to said relatively high-resistance path to be interrupted subsequently by said arcing contacts, and means for tripping said first-mentioned means upon opening the door of said casing for causing interruption of the circuit through said circuit breaker.

9. In a load-disconnecting device, the combination of a casing and a door for closing an open side of said casing, a circuit interrupter mounted on said door including an expulsion tube and a pair of relatively movable arcing contacts mounted therein, means for causing interruption of said circuit in said expulsion tube upon opening the door of said casing.

10. In a load-disconnecting device of the type including a casing with a door for closing an open side of said casing, an electric circuit interrupter mounted on said door, means for resetting said circuit interrupter after circuit interruption thereby merely by moving said door first in one direction and then in the other.

11. In a circuit interrupter, the combination of a casing and a door for closing an open side of said casing, an electric circuit breaker mounted on said door comprising a pair of relatively movable current-carrying contacts, means for maintaining said contacts in current-conducting relationship, means for separating said contacts in response to abnormal current conditions, and expulsion type interrupter connected in parallel with said current-carrying contacts and said abnormal current responsive means and means dependent upon the opening and closing of said door for reclosing said contacts to re-establish an electric circuit therethrough.

12. In a circuit interrupter, the combination of a casing and a door for closing an open side of said casing, an electric circuit breaker mounted on said door comprising a pair of relatively movable current-carrying contacts, latching means for maintaining said contacts in current-conducting relationship, said latching means being responsive to abnormal current conditions, means for separating said contacts upon release of said latching means, a conducting path connected in parallel with said latching means and said current-carrying contacts including a pair of relatively movable arcing contacts connected in series with a rod formed of a material furnishing a higher impedance to the current flowing through said circuit breaker than the circuit through said current-carrying contacts, said rod being arranged to extend out of said casing upon circuit interruption to indicate the condition of said circuit interrupter.

13. In an electric circuit interrupter, a pair of relatively movable current-carrying contacts, spring means tending to cause separation of said contacts, a bimetallic latch responsive to abnormal current conditions connected in series with said contacts for holding them in current-conducting engagement under normal current conditions and permitting said spring means to become effective under abnormal current conditions, a current-conducting path connected in parallel with said current-carrying contacts and said bimetallic latch including a pair of relatively movable arcing contacts, means for causing said current-carrying contacts and said bimetallic latch to carry substantially all of the current flowing through said circuit breaker under normal current conditions, means for causing the current to be diverted to said parallel conducting

path upon release of said bimetallic latch so that said bimetallic latch is immediately relieved from carrying the abnormal current upon separation of said current-carrying contacts.

14. In an electric circuit interrupter adapted for use in place of conventional fuse cutouts, the combination of a casing and a cover for closing an open side of said casing, a circuit interrupter mounted on said cover comprising a pair of relatively movable contacts, means for causing relative separation of said contacts to interrupt the circuit associated with said circuit interrupter, and means dependent upon the opening of said cover for effecting the closure of said contacts.

15. In an electric circuit interrupter adapted for use in place of conventional fuse cutouts, the combination of a casing and a cover for closing an open side of said casing, a circuit interrupter mounted on said cover comprising a pair of relatively movable contacts, bimetallic means for initiating relative separation of said contacts to interrupt the circuit associated with said circuit interrupter, and means dependent upon the opening and closing of said cover to re-establish an electric circuit through said contacts.

16. In an electric circuit interrupter, the combination of a casing and a cover for closing an open side of said casing, a circuit breaker mounted on said cover comprising a pair of relatively movable contacts, and means for causing relative separation of said contacts to interrupt the circuit associated with said circuit breaker, said circuit breaker being so constructed and arranged that said contacts may be reclosed to re-establish an electric circuit therethrough by movement of the cover of said casing.

17. In an electric circuit interrupter, the combination of a casing and a cover for closing an open side of said casing, a circuit breaker mounted on said cover comprising a pair of relatively movable contacts, and means for causing relative separation of said contacts to interrupt the circuit associated with said circuit breaker, said circuit breaker being so constructed and arranged that said contacts may be reclosed to re-establish an electric circuit therethrough by bodily movement of said circuit breaker.

18. In a circuit interrupter adapted for use in place of conventional fuse cutouts the combination of a casing and a cover for closing an open side of said casing, an electric circuit breaker mounted on said cover comprising a pair of relatively movable current carrying contacts, means for maintaining said current carrying contacts in current conducting relationship, arcing contacts associated with said current carrying contacts, means electrically connected in parallel with said arcing contacts for first causing separation of said current carrying contacts and then said arcing contacts in response to an abnormal current condition, and means dependent upon the opening and closing of said cover for reclosing said current carrying contacts to re-establish an electric circuit therethrough.

19. In a circuit interrupter adapted for use in place of conventional fuse cutouts the combination of a supporting insulator, a support for an electric circuit breaker mounted on said insulator and movable relative thereto, said circuit breaker comprising a pair of relatively movable current carrying contacts, means for maintaining said current carrying contacts in current conducting relationship, arcing contacts associated with said current carrying contacts, means electrically connected in parallel with said arcing

contacts for first separating said current carrying contacts and then said arcing contacts in response to an abnormal current condition, and means dependent upon movement of said support for effecting the closure of said current carrying contacts.

20. In a circuit interrupter, the combination of a casing and a cover for closing an open side of said casing, an electric circuit breaker mounted on said cover comprising a pair of relatively movable current carrying contacts, means for maintaining said contacts in current conducting relationship, means for separating said contacts in response to an abnormal current condition, arcing contacts associated with said current carrying contacts, and means for reestablishing the circuit through said current carrying contacts by movement of the cover of said casing.

21. In an electric circuit interrupter, the combination of a casing and a cover for closing an open side of said casing, a circuit breaker mounted on said cover comprising a pair of relatively movable current carrying contacts, means for maintaining said current carrying contacts in current conducting relationship, means for separating said current carrying contacts in response to an abnormal current condition, arcing contacts associated with said current carrying contacts, and means for operating said first mentioned means to permit separation of said arcing contacts upon opening the cover of said casing for interrupting the circuit through said circuit breaker.

22. In a circuit interrupter adapted for use in place of conventional fuse cutouts the combination of a casing, line terminals in said casing, a cover for closing an open side of said casing, an electric circuit breaker mounted on said cover and movable into and out of engagement with at least one of said line terminals in said casing, said electric circuit breaker comprising a pair of relatively movable current carrying contacts, means for maintaining said current carrying contacts in current conducting relationship, circuit interrupting means associated with said current carrying contacts, means electrically connected in parallel with said interrupting means for separating said current carrying contacts in response to abnormal current conditions to interrupt the circuit associated with said circuit interrupter, and means dependent upon the opening and closing of said cover for reclosing said current carrying contacts to re-establish an electric circuit therethrough.

23. In a circuit interrupting device, a pair of spaced terminals, bridging means normally electrically connecting said terminals and movable into and out of engagement with at least one of said terminals, means latching said bridging means to said one terminal to normally hold said bridging means in the closed circuit position, separable contacts carried by said bridging means biased to open circuit position, means for latching said separable contacts in the closed circuit position, and means responsive to one continuous movement of said bridging member for first unlatching said separable contact latching means and then unlatching said bridging means from said one terminal to permit the bridging means to be moved out of engagement with said one terminal.

24. In a circuit interrupting device, a pair of spaced terminals, bridging means normally electrically connecting said terminals and movable into and out of engagement with at least one of

said terminals, means latching said bridging means to said one terminal to normally hold said bridging means in the closed circuit position, separable contacts carried by said bridging means biased to open circuit position, means for latching said separable contacts in the closed circuit position, means responsive to one continuous movement of said bridging member for first unlatching said separable contact latching means and then unlatching said bridging means from said one terminal to permit the bridging means to be moved out of engagement with said one terminal, and means operable in response to movement of said bridging means to the open position for latching said separable contacts in the closed circuit position.

25. In a circuit interrupting device, a pair of disconnecting contacts, one of which is mounted on a movable contact support for movement therewith into and out of engagement with its cooperating contact, current interrupting contacts carried at all times by said movable support and connected in series with said disconnecting contacts, an operating mechanism for sequentially operating said contacts in a circuit opening operation to first open said interrupting contacts and to thereafter open said disconnecting contacts, and means operable to automatically open said current interrupting contacts independently of movement of said disconnecting contacts in response to currents above a predetermined value.

26. In a circuit interrupting device, a pair of disconnecting contacts, one of which is mounted on a movable contact support for movement therewith into and out of engagement with its cooperating contact, current interrupting contacts carried at all times by said movable support and connected in series with said disconnecting contacts, means for sequentially operating said contacts in both a circuit closing and a circuit opening operation, and additional means for automatically opening said current interrupting contacts independently of movement of said disconnecting contacts in response to the passage through the device of currents greater than a predetermined magnitude.

27. In a circuit interrupting device, a pair of disconnecting contacts, one of which is mounted on a movable contact support for movement therewith into and out of engagement with its cooperating contact, current interrupting contacts carried at all times by said movable support and connected in series with said disconnecting contacts, snap-acting means for operating said current interrupting contacts, means for sequentially operating said snap-acting means and said movable support to sequentially operate said current interrupting contacts and said disconnecting contacts, and means for causing automatic operation of said snap-acting means to open said current interrupting contacts independently of movement of said disconnecting contacts in response to the passage through the device of currents above a predetermined value.

28. In a circuit interrupter, an arc extinguishing device mounted for bodily movement, a pair of disconnecting contacts, one of said disconnecting contacts being movable with said arc extinguishing device into and out of engagement with the other of said disconnecting contacts, a pair of arc establishing contacts both of which are supported at all times by said arc extinguishing device and connected in series with said disconnecting contacts, operating means for both of

said pairs of contacts, operable to open said arc establishing contacts while said disconnecting contacts remain engaged, and thereafter to move said arc extinguishing device to open the circuit at said disconnecting contacts, and means operable to cause said operating means to automatically open said arc establishing contacts independently of movement of said disconnecting contacts in response to passage through the interrupter of currents above a predetermined magnitude.

29. In a circuit interrupter, an arc extinguishing device mounted for bodily movement, a pair of disconnecting contacts, one of said disconnecting contacts being movable with said arc extinguishing device into and out of engagement with the other of said disconnecting contacts, said arc extinguishing device having a pair of arc establishing contacts connected in series with said disconnecting contacts, means responsive to the opening movement of said movable disconnecting contact for sequentially opening said arc establishing contacts and said disconnecting contacts and to the closing movement of said movable disconnecting contact for sequentially closing said arc establishing contacts and said disconnecting contacts, and means independent of the movement of said movable disconnecting contact for opening said arc establishing contacts.

30. In an interrupter, a pair of spaced terminals, a hollow switch member for bridging said terminals, said bridging member having a contact thereon engageable with one of said terminals, circuit interrupter means in said hollow switch member connected to the other terminal and said contact and operable to interrupt a circuit between said terminals when said switch member is in bridging position, means responsive to one continuous movement of said bridging member to first open said interrupting contacts and then swing said switch member to open position, and means operable in response to predetermined conditions to cause said mechanism to automatically open said interrupting contacts.

31. In a circuit interrupting device, a movably mounted enclosure, a pair of disconnecting contacts, one of which is movable with said enclosure into and out of engagement with the other of said disconnecting contacts, arc establishing contacts within said enclosure and connected in series with said disconnecting contacts, operating means responsive to one continuous movement of said enclosure for sequentially operating said contacts and including means on said enclosure operable in response to the passage therethrough of currents above a predetermined magnitude to open at least said arc establishing contacts.

32. In a circuit interrupting device, a movably mounted tubular arc extinguishing device, a pair of disconnecting contacts one of which is movable with said arc extinguishing device into and out of engagement with the other of said disconnecting contacts, arc establishing contacts within said arc extinguishing device and connected in series with said disconnecting contacts, operating means responsive to one continuous movement of said arc extinguishing device for sequentially operating said contacts and including means operable in response to the passage therethrough of currents above a predetermined magnitude to open at least said arc establishing contacts.

33. In a circuit interrupter, an arc extinguishing device mounted for bodily movement, a pair

of disconnecting contacts, one of said disconnecting contacts being movable with said arc extinguishing device into and out of engagement with the other of said disconnecting contacts, said arc extinguishing device having a pair of arc establishing contacts connected in series with said disconnecting contacts, means responsive to the opening movement of said movable disconnecting contact for sequentially opening said arc establishing contacts and said disconnecting contacts and to the closing movement of said movable disconnecting contact for sequentially closing said arc establishing contacts and said disconnecting contacts, and current responsive means for opening said arc establishing contacts independently of the movement of said disconnecting contacts, whereby said arc establishing contacts may be opened by said current responsive means while said disconnecting contacts are closed.

34. In a circuit interrupting device, insulating support means, a pair of disconnecting contacts mounted on said support means, one of said contacts being mounted for movement into and out of engagement with the other to insert a large visible air gap in the circuit when in open position, current interrupting contacts also mounted on said support means and arranged in series circuit relation with said disconnecting contact, an operating mechanism operable in response to movement of said movable disconnecting contact for sequentially operating said contacts in a circuit opening operation to first open said interrupting contacts and to thereafter open said disconnecting contacts, and means operable to automatically open said current interrupting contacts in response to currents above a predetermined value.

35. In a circuit interrupting device, insulating support means, a pair of disconnecting contacts mounted on said support means, one of said contacts being mounted for movement into and out of engagement with the other to insert a large visible air gap in the circuit when in open position, current interrupting contacts also mounted on said support means and arranged in series circuit relation with said disconnecting contacts, means responsive to movement of said movable disconnecting contact for sequentially operating said contacts in both a circuit closing and a circuit opening operation, and additional means for automatically opening said current interrupting contacts in response to the passage through the device of currents greater than a predetermined magnitude.

36. In a circuit interrupting device, insulating support means, a pair of disconnecting contacts mounted on said support means, one of said contacts being mounted for movement into and out of engagement with the other to insert a large visible air gap in the circuit when in open position, current interrupting contacts also mounted on said support means and arranged in series circuit relation with said disconnecting contacts, snap-acting means for operating said current interrupting contacts, means responsive to movement of said movable disconnecting contact for sequentially operating said snap-acting means and said movable support to sequentially operate said current interrupting contacts and said disconnecting contact, and means for causing automatic operation of said snap-acting means to open said current interrupting contacts in response to the passage through the device of currents above a predetermined value.

37. In a circuit interrupting device, insulating

support means, a pair of disconnecting contacts mounted on said support means, one of said contacts being mounted for movement into and out of engagement with the other to insert a large visible air gap in the circuit when in open position, current interrupting contacts also mounted on said support means and arranged in series circuit relation with said disconnecting contacts, common operating means for said disconnecting and interrupting contacts including means responsive to the opening movement of said movable disconnecting contact for sequentially opening said current interrupting contacts and said disconnecting contacts and to the closing movement of said movable disconnecting contact for sequentially closing said current interrupting contacts and said disconnecting contacts, and means independent of movement of said movable disconnecting contact for opening said current interrupting contacts.

38. In a circuit interrupting device, insulating support means, a pair of disconnecting contacts mounted on said support means, one of said contacts being mounted for movement into and out of engagement with the other to insert a large visible air gap in the circuit when in open position, current interrupting contacts also mounted on said support means and arranged in series circuit relation with said disconnecting contacts, common operating means for said disconnecting and interrupting contacts including means responsive to the opening movement of said movable disconnecting contact for sequentially opening said current interrupting contacts and said disconnecting contacts and to the closing movement of said movable disconnecting contact for sequentially closing said current interrupting contacts and said disconnecting contacts, and current responsive means for opening said arc establishing contacts independently of the movement of said disconnecting contacts, whereby said arc establishing contacts may be opened by said current responsive means while said disconnecting contacts are closed.

39. In a circuit breaker adapted for use in

place of conventional fuse cutouts the combination of a casing and a cover for closing an open side of said casing, an electric circuit breaker mounted on said cover comprising a pair of relatively movable current carrying contacts, means for maintaining said contacts in current conducting relationship, arcing contacts associated with said current carrying contacts, means electrically connected in parallel with said arcing contacts for first separating said current carrying and then said arcing contacts in response to abnormal current conditions, and means dependent upon the opening and closing of said cover for reclosing said contacts to re-establish an electric current therethrough.

SIDNEY R. SMITH, JR.
